UNITED STATES PATENT OFFICE.

RAYMOND G. COOPER, OF SUGAR LOAF, NEW YORK, ASSIGNOR OF ONE-HALF TO
CHAS. C. TEGETHOFF, OF NEW YORK, N. Y.

COMBINED SHADE AND CURTAIN HOLDER.

1,095,311.

Specification of Letters Patent.

Patented May 5, 1914.

Application filed December 13, 1913. Serial No. 806,554.

To all whom it may concern:

Be it known that I, RAYMOND G. COOPER, a citizen of the United States, residing at Sugar Loaf, in the county of Orange and 5 State of New York, have invented certain new and useful Improvements in Combined Shade and Curtain Holders, of which the following is a specification, reference being had to the accompanying drawings.

10 This invention relates to new and useful improvements in combined shade and curtain holders and the primary object of the invention is to provide an improved device of this character which may be quickly and 15 readily applied to window frames without the use of nails and the like and which may be readily adjusted to fit any size window frame or any size of shade desired to be used in connection therewith.

20 Still another object of the invention resides in providing a device formed of sections coupled one to the other and a still further object of the invention resides in providing a device which is simple and durable in construction, inexpensive to manufacture and one which will be very efficient and useful in operation.

With these and other objects in view, the 30 invention consists in the novel features of construction, combination and arrangement of parts as will be hereinafter referred to and more particularly pointed out in the specification and claim.

In the accompanying drawing forming a 35 part of this application, Figure 1 is a front elevation of a window frame showing a combined curtain shade support constructed in accordance with my invention applied to use thereon. Fig. 2 is a horizontal section 40 through the device, as seen on line 2—2, Fig. 1; and Fig. 3 is a transverse section through the same as seen on line 3—3, Fig. 1.

In describing my invention, I shall refer 45 to the drawing in which similar reference characters designate corresponding parts throughout the several views and in which—

1 indicates a window frame of the usual or any preferred type to which is adapted to be applied my improved combined device, 50 for supporting a curtain pole and shade holder.

My improved invention comprises a pair of elongated U-shaped members 2 which are formed preferably of heavy wire or other 55 light metal, the base portions of which are

loosely linked together by means of a coupling or the like 3. The arms of the substantially U-shaped members 2 are looped immediately adjacent their ends to form pairs of alining eyes or keepers 4 and the 60 extreme free ends of the arms of these members 3 continuing from the eyes are bent and sharpened to form engaging prongs 5. These prongs 5 are adapted to be engaged with the sides or the front faces of the 65 frame, immediately adjacent the upper edge thereof, thus supporting the complete device in position on the window frame. These members 2 are capable of slight adjustment with respect to one another in view of the 70 coupling 3 and adapted to be received in the alining eyes or keepers 4, are the shanks of the curtain pole supports 6. A bolt 7 is adapted to be received in the eyes or ring-like portions of the supports, whereby an 75 ornamental curtain may be hung from the device to cover the window opening in the frame. This device is also designed to carry the shade supports and, to this end, a pair of shade supports 8 are provided. 80 These shade supports are substantially of the same design as the usual shade supports, with the exception of the angular base pieces. These base pieces are usually provided with openings for nailing or screwing 85 the same to the window frame but, in my improved device, these nail or screw openings are omitted and, in their stead, the ends of the base pieces are provided with flanges which are rolled to provide sleeve-like portions 9 thereon. These sleeve-like portions receive therethrough the arms of the substantially U-shaped members 2 and, in view 90 of the particular construction, admit of the shade supports being adjusted on said members 2. These flanges which form the sleeve-like portions 9 may be readily rolled about the arms of the members 2 in the application of the shade supports to use and, in applying the device to the window frame, the 95 same is secured flatly against the front face of the frame, at the top portion thereof, so as to cause the sleeve-like portions 9 to frictionally engage with the frame, thus retaining 100 said shade supports in their various adjusted positions on the device. From the above description of the construction of my improved device, the operation thereof will be readily understood and it will be seen 105 that I have provided a combined curtain 110

2
pole and shade support which may be quickly and readily applied to use and removed, when desired, and which is capable of ready and quick adjustment to accommodate curtain poles and shades of various sizes. It will also be seen that the device is one which is simple and durable in construction, inexpensive to manufacture and one which will be very efficient and useful in 10 operation.

While I have particularly described the elements best adapted to perform the functions set forth, it is obvious that various changes in form, proportion and in the 15 minor details of construction may be resorted to without departing from the spirit or sacrificing any of the principles of the invention.

Having thus described this invention, 20 what I claim is:—
A combined window shade and curtain

fixture comprising two elongated members substantially U-shaped in form and adapted to align when in operative position and having the free extremities of their stems directed outwardly, a link member engaging the bases of the U-shaped members and pivotally connecting one to the other, the free extremities of the stems of each of the U-shaped members being bent to provide alining eyes 25 and being pointed to afford a penetrating means, pole supports disposed through the alining eyes of the U-shaped members, and shade supports slidably engaged with the stems of the U-shaped members. 30

35 In testimony whereof I hereunto affix my signature in the presence of two witnesses.

RAYMOND G. COOPER.
